UNITED STATES PATENT OFFICE.

ORA A. COLBY, OF LARIMER, PENNSYLVANIA, ASSIGNOR TO WESTINGHOUSE ELECTRIC
AND MANUFACTURING COMPANY, A CORPORATION OF PENNSYLVANIA.

CONTROL APPARATUS.

1,321,509.

Specification of Letters Patent.

Patented Nov. 11, 1919.

Application filed September 25, 1914, Serial No. 863,508. Renewed April 12, 1919. Serial No. 289,744.

To all whom it may concern:

Be it known that I, ORA A. COLBY, a citizen of the United States, and a resident of Larimer, in the county of Allegheny and 5 State of Pennsylvania, have invented a new and useful Improvement in Control Apparatus, of which the following is a specification.

My invention relates to control apparatus, 10 and it has special reference to liquid rheostats of the type commonly employed for governing the operation of polyphase induction motors.

One of the objects of my invention is to 15 improve and simplify the construction and operation of devices of the character referred to and to provide a rheostat which shall be particularly compact and durable in construction and shall be capable of 20 ready manipulation by reason of the peculiar relationship of parts.

Another object of my invention is to provide a liquid rheostat having a regulatable discharge valve and a plurality of sets of 25 relatively rotatable electrodes through which a continuous flow of electrolyte is preferably maintained for the purpose of carrying away the heat.

In the accompanying drawing, Figure 1 30 is a plan view of a rheostat constructed in accordance with my invention, the cover and certain portions of the operating mechanism being removed for the sake of clearness; Fig. 2 is a view, partially in side 35 elevation and partially in section, of the apparatus shown in Fig. 1, the section being taken along the plane of II-II of Fig. 1; and Fig. 3 is a diagrammatic view showing the relationship of electrodes of a modified form of rheostat which is comprehended 40 in my invention.

Referring to the drawings, the apparatus shown comprises a tank 1 having a centrally disposed bottom discharge opening 2, an 45 inlet opening 3 through which electrolyte is preferably continuously circulated, a tubular member or discharge valve 4 coöperating with the discharge opening 2 and projecting upwardly into the tank 1, a supporting or bearing member 5 surrounding the lower end of the valve member 4 and secured to the bottom wall 6 of the tank, a 50 rotatable sleeve 7 resting upon the bearing member 5 and disposed around the dis-

charge valve 4 in such manner as to be rotated with respect thereto, a plurality of sets 8 of movable electrodes 9 that are secured to the sleeve 7, an operating mechanism 10 for actuating the discharge valve 4 and the sets 8 of rotatable electrodes, a 60 plurality of supporting frames 11 secured to and insulated from the tank 1, and a plurality of sets 12 of electrodes 13 which are rigidly secured to the supporting frames 11. 55

The tank 1 is preferably of plate construction and is supported upon a receiving reservoir 15 into which the electrolyte is discharged. The tank 1 is provided with a cover 17 through which the operating mechanism 10 projects. The lower end of 65 the tubular discharge valve 4 is provided with a tapered plug portion 18 which is adapted to coöperate with, and tightly fit into, the discharge opening 2. The upper end of the discharge valve 4 is provided 70 with a multi-arm yoke 20 which is secured thereto and which has a rigid connection to an operating rod 21, by means of which said valve 4 may be raised and lowered in 75 position to effect the opening and the closing of the discharge port 2.

The supporting and bearing member 5 comprises an annular portion 23 of L-shaped section to which a plurality of feet 24 are connected, said feet resting upon the bottom 80 wall 6 of the tank and being suitably fixed thereto. The sleeve 7 is seated within the L-shaped portion 23 of the bearing member 5 and has bearing surfaces 26 and 27 at its 85 respective ends which slidably engage the outer surface of the valve member 4 and permit rotative movement of said sleeve with respect to said valve, with a minimum 90 frictional resistance.

The upper end of the sleeve 7 is provided 95 with outwardly projecting lugs 28 which are engaged by a plurality of rods 29 that are fixed to a yoke 30, which is provided with a central portion 31 that projects upwardly through the cover 17 and is concentrically related to the operating rod 21. The upper end of the projecting portion 31 of the yoke 30 has associated therewith a gear wheel 32 which is adapted to engage 100 a suitably driven member (not shown) for 105 the purpose of effecting a rotative movement of the sleeve 7 and its associated set 8 of electrodes 9.

The several sets 8 of electrodes 9 are radially disposed and substantially equally spaced, and the several electrodes 9 constituting said sets are each of sectorial form 5 and are disposed one above another, in side-by-side horizontal relation, being suitably secured to the sleeve 7.

The supporting frames 11 are located intermediate the sets 8 of electrodes, and each frame 11 is supported, at its lower end, upon an insulating block 35, and its upper end is secured and electrically connected to a conducting rod 36 which projects through the cover 17 and is insulated therefrom by means of an insulator 37. The several electrodes 13 are also sectorial in form and are rigidly fastened to the supporting frame 11, being also disposed horizontally one above another, although at heights intermediate 15 those of the rotatable electrodes 9. Thus, when the sets 8 of rotatable electrodes 9 are rotated from the positions shown in the drawing, the electrodes 9 are interposed between the electrodes 13 of the stationary 20 groups or sets 12, whereby the working surfaces of the respective sets of electrodes are brought into proximity, and, therefore, the resistance of the electrolyte between them is reduced accordingly.

According to my invention, the continuously inflowing electrolyte through the inlet port 3 rises between the coöperating sets 25 of electrodes and finally overflows into the discharge valve 4 and is thence discharged into the receiving reservoir 15. Obviously, in order to empty the tank 1 of electrolyte suddenly, it is necessary to cause the operating rod 21 to raise the discharge valve 4, thereby permitting electrolyte to rapidly 30 discharge through the opening 2.

In Fig. 3 I have shown diagrammatically a liquid rheostat 40 having a modified form of electrodes. In this apparatus, sets 41 of vertically disposed grouped electrodes 45 42 are provided which are adapted to co-operate, in the usual way, with sets 43 of similarly disposed and grouped electrodes 44, the latter sets of electrodes 44 being mechanically associated with the sleeve 7^a and 50 adapted for rotative movement with respect to sets 41 of electrodes 42 through the agency of suitable means such, for instance, as that already described.

The specific structural details and arrangement and location of parts of the apparatus set forth may be modified considerably within the scope of my invention, and I have intended to cover such modifications in the appended claims.

I claim as my invention:

1. In a liquid rheostat, the combination with respectively stationary and movable sets of electrodes normally disposed in substantially horizontal edge-to-edge relation, 65 of means for effecting relative rotative

movement thereof, whereby the respective active surfaces of said electrodes are brought into vertical proximity.

2. A liquid rheostat comprising a tank and a plurality of sets of horizontally disposed relatively rotatable sectorial electrodes. 70

3. A liquid rheostat comprising a tank, a plurality of spaced sets of stationary electrodes, a plurality of sets of movable electrodes interposed between said spaced sets of electrodes and means for rotatively moving the sets of movable electrodes intermediate the electrodes of said adjacent stationary sets of electrodes. 75

4. A liquid rheostat comprising a tank and a plurality of relatively rotatable horizontally disposed electrodes. 80

5. A liquid rheostat comprising a tank, a plurality of spaced stationary sets of horizontally disposed sectorial electrodes, a plurality of horizontally disposed sets of sectorial electrodes interposed between said spaced stationary electrodes, and means for imparting rotative movement to said stationary electrodes. 85

6. A liquid rheostat comprising a tank, a centrally disposed tubular discharge valve associated therewith, and a plurality of relatively movable sets of electrodes between 95 said tubular valve and said tank.

7. A liquid rheostat comprising a tank, a tubular member projecting upwardly into said tank, a set of electrodes associated with said member, and a coöperating set of electrodes associated with said tank and co-operating therewith. 100

8. A liquid rheostat comprising a tank, a tubular member projecting upwardly into said tank and adapted to be raised and lowered, and a set of radially disposed electrodes associated with said member. 105

9. A liquid rheostat comprising a tank, a tubular member projecting upwardly into said tank and adapted to be raised and lowered, a plurality of horizontal and radially disposed electrodes between said member and said tank, and means for imparting rotative movement to said electrodes. 110

10. A liquid rheostat comprising a tank, 115 a centrally disposed tubular member adapted to be raised to permit the discharge of electrolyte, a sleeve surrounding said member, and a plurality of radially disposed electrodes fixed to said sleeve.

11. A liquid rheostat comprising a tank having a central discharge opening, a tubular valve member adapted to close said opening and to be raised to permit the discharge of electrolyte therethrough, and a plurality 125 of rigidly associated electrodes disposed around said valve member, and means for imparting rotative movement to said electrodes.

12. A liquid rheostat comprising a tank 130

- having a central discharge opening, a tubular valve member adapted to close said opening and to be raised to permit the discharge of electrolyte therethrough, a bearing and 5 supporting member disposed around the lower end of said valve member, a rotatable sleeve resting upon said bearing and supporting member, and radially disposed electrodes fixed to said sleeve.
- 10 13. In a liquid rheostat, the combination with a tank, of a stationary structure supported thereby and insulated therefrom, and horizontally disposed inwardly projecting electrodes secured thereto.
- 15 14. In a liquid rheostat, the combination

with a tank having a bottom discharge opening, a tubular discharge valve coöperating with said opening, and a plurality of electrodes rotatably mounted around said valve member, of concentric means for raising and 20 lowering said valve member and for effecting rotative movements of said electrodes.

In testimony whereof, I have hereunto subscribed my name this 19th day of Sept., 1914.

ORA A. COLBY.
